UNITED STATES PATENT OFFICE

157,023

SCAFFOLD HORSE

Dabney Ashenfelter, Swanton, Ohio, assignor to
Bil-Jax, Inc., Archbold, Ohio, a corporation of
Ohio

Application June 10, 1948, Serial No. 146,880

Term of patent 14 years

(Cl. D54—1)

To all whom it may concern:

Be it known that I, Dabney Ashenfelter, a citizen of the United States, and resident of Swanton, in the county of Fulton and State of Ohio, have invented a new, original, and ornamental Design for a Scaffold Horse, of which the following is a specification, reference being had to the accompanying drawings, forming a part thereof.

In the drawings, Fig. 1 is a perspective view of a scaffold horse showing my new design; Fig. 2 is a top plan view thereof, and Fig. 3 is an end view thereof. Both sides are the same and both ends are the same in appearance.

The essential features of the design reside in those portions shown in full lines.

I claim:

The ornamental design for a scaffold horse, substantially as shown and described.

DABNEY ASHENFELTER.
